UNITED STATES PATENT OFFICE.

JOHN PETER WEIS, OF NYACK, NEW YORK, ASSIGNOR OF ONE-HALF TO METROPOLITAN SEWING MACHINE CORPORATION, OF NYACK, NEW YORK, A CORPORATION OF DELAWARE.

LUBRICATING SYSTEM AND SEWING-MACHINE CONSTRUCTION.

1,348,527.

Specification of Letters Patent.

Patented Aug. 3, 1920.

Original application filed October 16, 1914, Serial No. 867,005. Divided and this application filed April 29, 1916, Serial No. 94,354. Renewed December 24, 1919. Serial No. 347,190.

To all whom it may concern:

Be it known that I, JOHN PETER WEIS, a citizen of the United States; residing at Nyack, in the county of Rockland and State of New York, have invented certain new and useful Improvements in Lubricating Systems and Sewing-Machine Constructions, of which the following is a specification.

10 This invention is an improvement in sewing machines with or without stop-motions, and involves constructional arrangements whereby thorough and constant lubrication is obtained for sewing machine and stop-motion parts, either or both. The sewing machine and stop motion illustrated are high-speed mechanisms in which serious heating would occur were the necessary parts not thoroughly and constantly lubricated while the mechanisms are in action.

15 My invention is generally applicable to sewing machines embodying features of my present invention independently of any embodiment of those features of the invention 20 which relate to the stop-motion for the drive-shaft of the sewing machine.

This application is a division of my application Serial No. 867,005 for sewing machine and cutting mechanism therefor, filed 25 October 16, 1914, and which describes features of improvement on the combined cutting-and-sewing machine shown in my United States Patent No. 1,114,082, of October 20, 1914.

30 In the accompanying drawings forming part hereof,

Figure 1 is a top plan view of a portion of the combined cutting-and-sewing machine mentioned. This view shows two sewing 35 machine heads and for each head one member of a stop-motion. The view is particularly useful in locating parts illustrated in other figures.

Fig. 2 is a lengthwise sectional view of 40 one of the sewing machine heads at line 2—2 of Fig. 1. This view shows an oil reservoir and pump carried by one of the sewing machine heads, the construction and arrangement of the top drive-shaft and of the 45 looper shaft and of various connections between the two, together with the means for driving the oil pump and a portion of the stop motion, in lengthwise central section, for the top drive-shaft of a sewing machine,

Fig. 3 is a sectional elevation at line 3—3 of Fig. 7 and illustrates the oil reservoir and oil pump with a portion of the pump driving belt which also drives the top shaft of a sewing machine.

Fig. 4 is a perspective view of a pair of pump gears.

Fig. 5 is a face view of the pump casing with its cover plate removed; and

Fig. 6 is an inner face view of the pump casing cover plate removed.

Fig. 7 is a side elevation of the oil reservoir, oil pump, driving pulley and a portion of a driving belt, the wall of the reservoir being broken away to show an interior oil filtering chamber wall of the oil reservoir. The belt shown is for driving the top shaft of the sewing machine and also for driving the oil pump.

Fig. 8 is a view partly in side elevation and partly in vertical section at line 8—8 of Fig. 1, and shows the top drive shaft of a sewing machine head with a stop motion therefor and a stop motion control lever provided with means for holding a shock-absorbing body of oil.

Fig. 9 is a rear end view of the stop-motion control lever and of its pivoted stop finger.

Fig. 10 is a side elevation of the rearward end portion of the stop-motion control lever and of the other parts shown in Fig. 9.

Fig. 11 is an elevational view partly in full lines and partly in lengthwise central section, of a thimble-forming part of the construction of the rearward oil-receiving and oil-holding end of the stop motion control lever.

Figs. 12 and 13 are respectively side and end elevations of a perforated sleeve for receiving the thimble shown in Fig. 11, the sleeve being adapted for a threaded connection with a chamber in the rearward end of the aforesaid lever.

Fig. 14 is a view partially in elevation and partly in vertical central section, at a line 100 corresponding to line 14—14 of Fig. 15, and shows a rearward portion of the top shaft of a sewing machine head provided with a pulley for driving such shaft and for clutching the stop motion thereof. The 105 view also shows certain details of the stop motion, including a recess for a brake shoe omitted from the view.

Fig. 15 is a view partially in elevation and partly in transverse section at line 15—15 of Fig. 14, and shows the driving and clutch pulley together with details of 5 the stop motion. This view shows the stop-motion balls in a clutched position by engagement with a ball-retaining ring clamped in the belt wheel.

Fig. 16 is a view similar to Fig. 15 but 10 shows stop-motion wedges and balls in non-clutching position.

Fig. 17 is an end elevation of the rearward end portion of the top drive shaft and illustrates in end view a lengthwise-extending 15 key on the rearward end of the drive shaft.

Fig. 18 is a side elevation of the rearward end portion of said drive shaft, and shows the lengthwise-extending key together with 20 wedge-receiving pockets in a portion of the drive-shaft.

Fig. 19 is a tubular sleeve of varying diameters, a portion of which forms a ball retainer, and another portion of which forms 25 a stop tooth. This sleeve is a member of the stop motion and has portions acted on by a brake shoe.

Fig. 20 is a transverse sectional view of 30 said sleeve at line 20—20 of Fig. 19.

Fig. 21 is an end elevation of the rearward end of the top drive-shaft and of the driving and clutch pulley in assemblage with the parts shown in Figs. 18, 19, 20, and other figures.

Fig. 22 is a perspective view of one of the ball-receiving wedges forming part of the stop motion.

Fig. 23 shows in two views a brake shoe forming a part of the stop motion.

Fig. 24 is a view partly in elevation and partly in transverse central section at line 24—24 of Fig. 14, and illustrates the construction of the rear end bearing for the 45 stop sleeve shown in Fig. 14 for the rearward end portion of the top-shaft. The brake shoe is indicated in plan by dotted lines.

Fig. 25 shows in elevation and end view 50 a brake-shoe pressure-plug forming part of the stop-motion.

Fig. 26 is a perspective view of the brake-shoe lifting lever forming a part of the stop motion.

Fig. 27 is an enlarged view of the needle holder guide, to show more clearly the oil conduits in these parts.

Referring to the drawings, the two sewing machine heads together with their respective stop-motions are identical. Description 60 of one sewing machine and of one stop-motion will therefore be sufficient. The sewing machine head comprises an upper horn A, an under horn A', and a connecting trunk a, the horns and trunk having 65 communicating chambers. The outer wall

of the trunk comprises an inwardly projecting boss a' in the inward end of which stop-motion members are arranged in operative relation to the rear end of the top or needle-bar drive-shaft. The upper side of the 70 upper horn A is provided with a covered opening at a² for access to the chamber of the trunk, and the outer end wall is provided with an opening a³ through which the lubricant is poured into an oil container carried 75 by a lower part of the trunk. The rear wall of the trunk is also provided with a covered opening a⁴ into a lengthwise-extending chamber of the boss a' for observation of the lubricant through the transparent cover 80 a⁵ in the chamber of the boss a', the rearward portion of such chamber forming an oil space and the forward portion forming a housing. The top drive-shaft and the looper shaft hereinafter described are both 85 tubular and each is inclosed between its ends for the greater part of its length in tubes hereinafter described, which are centered and held in the lengthwise-extending chambers of the horns by set-screws a⁶ through 90 the horns and impinging on the outer surfaces of the tubes.

Lubricating system and sewing machine head construction.—The oil reservoir 1 carried by the lower part of the trunk is supplied with oil through the opening a², the oil being poured into the drip-pan 2 which covers the top of the oil reservoir and also projects laterally thereof in the direction of and below the under horn A'. The trunk is 100 open at a⁷ on its under side. The drip-pan is provided over the rearward side of the reservoir with a depressed perforated bottom portion forming an oil strainer 3. From the drip-pan the oil flows into a compartment 4 at the rearward side of the reservoir which is interiorly provided with parallel vertical walls 5 that are spaced apart, the space containing filtering material 6. The walls 5 are numerously perforated at 7 and the oil flows from compartment 4 through the perforations in the walls 5 and the filtering material between them into the compartment 8 wherein an oil pump is located. The drip-pan has a vertically walled opening 9 through it for passage of a belt B that drives the pump. The induction tube 10 of the pump extends downwardly toward the bottom of compartment 8 and the eduction tube 11 extends upwardly from the pump through the chamber of the trunk to conduct the pumped oil to the oil conduit 12 in the top of the boss a'. The pump comprises two small thin spur gears 13 and 13^a, one of the gears being provided with trunnions 14 which are journaled in the side walls of the pump casing, and the other gear being fixed on a shaft 15 which is journaled in the side walls of said casing and has one of its ends extended to receive the 130

driving pulley 16. The pump casing comprises a recessed block and a cover therefor. The block has an elongated recess 17 of a depth of the thickness of the gears which 5 are the same thickness. The recess 17 has a length sufficient to receive the two gears when intermeshed. The block is provided with alined holes which lead from opposite sides of the recess 17. One hole is under 10 and the other above the gears, for reception respectively of the pump induction and eduction tubes 10 and 11 which are alined with the intermeshing peripheries of the two gears. The outward face of the block 15 has an annular recess the bottom 18 of which is flush with the outward surfaces of the intermeshing gears. The outward face of the block has another annular recess 19 concentric with, but of greater diameter than recess 18. The recess 19 is inclosed by the margins 20 of the outward face of the block which is indicated by 21. The cover is formed of a disk having on its inner face an annular projecting boss 22 of a diameter to 25 fit into a recess the bottom of which is indicated by 18 with the inward face of the boss close up to the outward faces of the intermeshing gears. The cover is also provided with an annular flange 23 which fits 30 into the recess 19 and is fixed air-tightly thereinto. Boss 22 is provided on its inner face with bearing holes 24 which extend only partway through the boss 22 and which support, one an end of the gear shaft 15, and 35 the other a trunnion of the gear 13^a. These bearing holes 24 are blind holes for insurance of air-tightness of the pump. The pump gears 13 and 13^a are shown full size, and so also is the entire pump structure in Figs. 40 5 and 6. It has been found in practice that a pint of oil can be passed through the sewing machine every three minutes by means of this pump which is practically efficient in keeping some oil-containing parts constantly 45 lubricated by cil spray produced by either the centrifugal or vibrating forces of the high-speed parts.

The top drive-shaft 25 is bored throughout its length to form an oil conduit 26, the 50 rearward end of this shaft projecting into the oil chamber 27 in the boss a', such chamber being supplied from the eduction tube 11 through the conduit or port 12 in the upper side of the boss a'. The front end of 55 the conduit 26 is plugged at 28. The front end of the top shaft has an exteriorly reduced portion 29 and in this portion its wall is drilled at 30 to form oil conduits leading from the conduit 26 and permitting the passage of oil therefrom to the front bearing 31 60 of this top shaft; the bearing 31 being fixed in an inclosing tube 32 which is held in place by the set-screws a'. The inclosing tube 32 projects forwardly beyond the front wall of 65 the front bearing 31 and forms a housing

33 for the needle-driving crank 34 fixed on the projecting end of the shaft 25. At its rear end, shaft 25 is fixedly united to a tubular ball crank member 25^a which forms a rearward prolongation of the top drive-shaft. The member 25^a is formed with two ball cranks 35 which are each drilled at 36 to form oil conduits from the lengthwise tubular chamber of the member 25^a to the bearings 38, one at the upper end of a connecting rod 39 and the other at the upper end of a connecting rod 39^a. The tubular ball crank member 25^a has its bore in alinement with the conduit 26 of the shaft 25 so that the conduit 26 extends from its front plug 28 rearwardly to the extreme outer end of such ball crank extension of the top drive-shaft. The rear end of the bore in said extension opens into oil chamber 27. Surplus oil from the ball cranks 35 and the bearings 38 flows down the connecting rods 39 and 39^a to the respective ball bearings 40 and 41 thereof at their lower ends. The wall of the conduit 26 within the inclosing end of its rearward extension 25^a is bored at 42 and the inclosing forward end of the member 25^a is coincidentally bored at 43 to form conduits from the conduit 26 to the rearward bearing 44 of the top drive-shaft 25, this rearward bearing being fixed in the rear end of the inclosing tube 32. The side wall of the front end of conduit 26 just rearwardly of the plug 28 is perforated at 45 exteriorly of the front bearing 31 and within the housing 33 to form an oil conduit leading from conduit 26 into an oil conduit 47 formed by drilling the needle-driving crank 34.

Conduit 47 discharges oil on the front advancing surface of the crank at one side of the crank pin 48 and such oil flows down the advancing surface of the rotating crank to and lubricates the crank pin in its bearing 49 which is formed in the upper end of the needle-driving link 50. Some of this oil flows out on the crank, and going to the crank-pin bearing, is whirled off by centrifugal force and caught within the housing 33; and other of the oil coming to the crank pin bearing flows down the needle link 50 to and lubricates the connection 51 of the needle link with the needle holder 53. This oil escaping at the connection 51 finds its way to the needle-holder guide-bar 54 and needle-holder ears 55 that reciprocate vertically in the groove 56 of the needle-holder guide 57. The oil passing through the conduit 47 is forced thereinto by centrifugal force and it is found in practice that the amount of oil finally coming to the needle holder and needle-holder guide is, while sufficient for lubrication purposes, negligible so far as any deposit of oil on the goods is concerned.

The shank of the needle-holder guide 57 is formed with an oil conduit 58 (Fig. 27) 130

which extends downwardly to near the bottom of the needle-holder guide-bar 54, the wall of conduit 58 being perforated at 59 to permit escape of oil to the outer surface 5 of the needle-holder guide-bar.

The top-shaft-inclosing tube 32 at its forward end and lower portion, has a transverse web 60, or in other words the housing 33 has such transverse web which forms a 10 dam to hold back in the housing any oil if it drop to the bottom thereof. The front bearing 31 is formed on its under side with a lengthwise conduit 61 that conducts oil rearwardly into the tube 32 from the bottom of 15 the housing 33; and such oil flows rearwardly through the conduit 61 along the bottom of the tube 32 to oil-conduit 62 which is formed in the bottom of the rearward bearing 44 of the top shaft.

20 The rear end of conduit 62 discharges within a housing or cap 63 which is open at its under side. This cap incloses the rearward end of the tube 32 and has at its rear end an opening for reception of the 25 flanged end of the pulley hereinafter described. The under sides of the housing or cap 63 are curved laterally inward at 64 giving the housing 63 a trough shape along its bottom both lengthwise and transversely thereof. Oil flowing into the chamber of the housing from conduit 62 flows along the adjacent edges 65 thereof to the drip point 66 which is directly over a V-shaped oil-receiving space 67 in the upper 30 side of a bell crank 68 one arm of which terminates in a ball 41^a working in the ball bearing 41, and the other arm of which terminates in a ball 69 which is entrant in the looper shaft. Oil so falling into the 35 space or opening 67 oils the crank of the bell crank journal and flows down the lower bell-crank arm to its end 69 which is within the rear end of the lengthwise-chambered looper-shaft 70, the upper side of this 40 looper shaft having a slot 70^a through which the lower end of the lower arm of the bell crank extends. Oil collecting in the chamber of the looper shaft at the lower end of the lower arm of the bell crank, flows 45 forwardly through conduits 71 in the plug 72 which is slidable in the chamber of the looper shaft just forwardly of the lower ball end 69 of the lower member of the bell crank. The oil flowing through these 50 conduits 71 passes the coil spring 73 which is mounted between the slidable plug 72 and a forward fixed plug 74 that forms an abutment within the chamber of the looper shaft for the forward end of the coil spring 55 73. The plug 74 is formed with conduits 75 whereby the oil flows therethrough and forwardly through the chamber of the looper shaft to the front end portion thereof, and thence through openings 76 in its 60 side wall for oiling its front bearing 77;

thence some of the oil escapes into the annular recess 78 on the front face of the bearing 77, from the lower portion of which recess 78 a conduit 79 extends downwardly and rearwardly into the chamber of a tube 70 80 which incloses a greater part of the length of the looper shaft, and in the front end of which the front bearing 77 of the looper shaft is fixed. The rear bearing 77^a of the looper shaft is fixed in the rear 75 end of the tube 80 which is centered in the chamber of the lower horn A' by set screws a⁶ similarly to the centering and fixing of the inclosing tube 32 for the top drive-shaft. The rear bearing 77^a is provided with a 80 rearwardly inclined conduit 81 which discharges into the forwardly projecting portion of the drip-pan, the bottom of which is inclined rearwardly to the oil strainer 3. The looper shaft has its rearward portion 85 within the rearward bearing 77^a provided with oil conduits 76^a for lubricating the looper shaft in its rearward bearing.

The connecting shaft 39 leading to the ball crank 40^a at the rear end of the looper shaft, serves to oscillate the looper shaft, the ball crank 40^a projecting from a plug 82 fixed in the rear end of the looper shaft.

The connecting rod 39^a at its lower end co-operates with the ball 41^a on the outer end of the upper arm of the bell crank 68 and reciprocation of this connecting rod 39^a, by means of the bell crank, the movable plug 72, the spring 73, and the fixed plug 74, secures endwise reciprocation to the 100 looper shaft in its front and rear bearings 77 and 77^a, the forward movement of the looper shaft being against the resistance of the spring 73 which is a mere take-up spring for wear on the plugs 72 and 82 and the 105 ball 69. Spring 73 is under heavy tension and the reciprocation of the looper shaft is positive in each direction. The ball connections formed by the ball cranks 35 and their bearings 38 and by the bearings 40 110 and 41 and the balls 40^a and 41^a and by the ball 69, secure easy actuation of the connecting rods 39 and 39^a for the rocking and endwise reciprocatory movements of the looper shaft.

The described inclosure of the top drive-shaft with the looper shaft each with a tube in the ends of which the bearings for each shaft are fixed, and the centering of these tubes respectively in the lengthwise-extending chambers of the upper and under arms of the sewing machine head, are novel features of importance in respect to economy of construction and assemblage. The lubricating system is of very great importance 125 and permits adequate lubrication while the machine is operating at very high speed, efficiently lubricating the mechanisms above described and also the stop motion for the sewing-machine drive-shaft. This stop mo- 130

tion forms the subject matter of a divisional application, Serial No. 94,355, filed April 29, 1916, of my said application Serial No. 867,005, and is supplied with oil from the reservoir 27 through the conduit 90. The set screws α^a are quarteringly disposed relatively to the tubes 32 and 80.

Sewing-machine stop-motion.—The shaft extension 25^a has its ball cranks 35 spaced apart one from the other, and rearwardly of these cranks it has an enlarged portion 91 formed circumferentially with three wedge-receiving pockets 92 at 120° apart, to receive the segmental wedges 93, the curved wall of each of which from its butt to its pointed end, is grooved at 94 in the direction of the curvature of the wedge to receive balls. The cross-section of the pockets is shown in Figs. 15 and 16, which also show the cross-section of the wedge shown in perspective in Fig. 22. The curved grooves 94 are eccentric to the axis of the top shaft, and the outward edges of the side walls 95 of each groove are concentric with the top shaft axis 25 and flush with the periphery of the enlargement 91. A stop sleeve 96 (Figs. 19, 14 and 15) has two interior and two corresponding exterior diameters. Portion 97 of the sleeve fits freely on the top-shaft enlargement 91 and holds the wedges 93 in the pockets 92. Portion 97 of sleeve 96 is provided with three openings 98 through its annular wall, spaced apart 120° to receive the balls 99, each of which lies projectingly in an opening 98, and also lies in a groove 94 of a wedge 93. A ball retaining ring 99^a forms part of the belt-wheel 100 which is made in two parts secured laterally together by screws 101, the ball retaining ring being secured 40 fixedly between them. The belt-wheel has a hub 102 projecting from each of its sides, the hub fitting loosely and running on the sleeve 96 which is exteriorly reduced in diameter at 103, 103, and exteriorly provided 45 with an interposed stop tooth 104 between the reduced portions 103, 103 which are of uniform exterior diameter. The tooth 104 is formed by grooving the outer wall of the sleeve 96 annularly and eccentrically to its 50 lengthwise axis between the portions 103. This eccentric groove is indicated by 105. The interior annular wall of the reduced portion of sleeve 96 has a lengthwise-extending key-slot 106 to receive a radially projecting key 107 formed on the outer end 108 of the top shaft extension 25^a adjacent the enlargement 91 (Figs. 17, 18 and 20). The interior wall of the reduced portion of the sleeve 96 is indicated by 109. The sleeve 96 55 is provided at the end of its reduced portion with a pin 110 extending in the direction of the length of the sleeve. One end of a coil spring 111 which is the stop-motion starting spring, is secured to this pin, and the other 60 end of the spring is connected by a pin 112

to the keyed portion 107 of the top shaft. An end bearing 113 for the sleeve 96 is cut out at 114 to receive a brake shoe, and also at 115, and is formed with a bore 116 (Fig. 24) wherein portions of the reduced portions 70 103 with other portions of the sleeve freely rotate in exposure to the brake shoe. A brake-shoe 117 (Figs. 8, 23 and 2) is mounted in the cut-out 114. The shoe has a lining 118 of babbitt or other metal or material, 75 and on its upper or back side has a slot 119 which receives the end 120 of a pressure-plug-lifting lever 121 (Figs. 26 and 8) which at 122 is pivoted in a housing for the stop-motion with one end projecting for actuation. Such housing is the front end portion of the chambered boss α' . The top of the brake shoe is concaved at 124 at right-angles to the slot 119 to receive the convex head 125 of the pressure-plug 126, the head being 80 slotted at 127 to receive the end 120 of the lever 121. A coil spring 128 (Fig. 8) surrounds the upwardly-extending stem of the pressure-plug 126 and a hollow screw 129 surrounding the stem of the pressure plug 90 is mounted in the housing mentioned to regulate the pressure of the spring the under end of which bears on the flange 123 of the pressure plug head. The housing is centrally chambered at 130 to receive the bearing 113 for the assembled sleeve 96 and shaft end 108 (Figs. 2, 8 and 14). The housing on its side opposite the pressure plug or on its under side in the form shown, has a radial slot 131 which communicates with the 100 cut-out 115 formed in the bearing 113. The housing, adjacent the pressure plug, is slotted at 132 to receive the pressure-plug-lifting lever 121 which at 122 is pivoted between side walls of the slot. The oil chamber 27 is at the outward end of the chambered boss or housing α' and is supplied with lubricant from the oil tube 11, the upper end of which overhangs and discharges into the oil-feed opening 12 formed vertically in 110 the upper wall of the housing. 105

Stop-motion control.—The sewing-machine trunk is provided with a bulging projection 134 at its upper front side. The front wall of the bulging projection is vertically slotted at 135 to receive the hub 136 of the stop-motion control lever 137 which is formed forwardly of its hub with a transverse opening 138 into which projects the 115 end of an adjusting screw 139 to engage the 120 end 140 of a trip lever 141, the end 140 projecting laterally into the hole 138 in opposition to the end of the adjusting screw 139. The stop-motion control lever 137 is fixed on a transverse rocker shaft 142 by set 125 screw 143. The ends of the rocker shaft 142 are journaled in bearings in the side walls of the slot 135 of projection 134, and the trip lever 141 which is loosely fulcrumed on the rocker shaft 142 is provided with an up- 130

wardly and forwardly projecting arm 143, the free end of which overlaps the forwardly projecting arm of the pressure-plug lever 121. The rear arm 144 of the controlling lever 137 projects into the chamber of the trunk and its upper side is recessed at 145 to hold a wire basket or the like 146 filled with filtering material 147, the basket or container being held in place by a staple 148. The recess 145 and filtering material hold lubricant supplied by the oil pump referred to, the lubricant falling into recess 145 from the conduit 90. An oil canal 149 extends forwardly from the bottom of the lubricant recess 145 through the end wall of a bore 150 in the rear end of the controlling-lever arm 144. The outer portion of this bore is tapped to receive a hollow annular bushing 151 having in its forward end a plug 152 secured to the bushing by a transverse pin 153. The plug has an integral rearwardly-extending stem 154. The outer or rearwardly-extending end of the bushing is threaded so as to be screwed into the tapped end of the bore 150, and forwardly of its threaded portion the bushing has a reduced exterior diameter through the side walls of which, just inwardly of the inner wall of the plug 152, oil holes 155 are formed. The annular wall of the bushing also has a series of annularly arranged oil holes 156 adjacent the inward end of its threaded portion. A sliding thimble 157, the rearward closed end of which is rounded off at 158, is mounted in the bore of the bushing 151, the tubular wall 159 of the thimble sliding freely in the bushing, and the thimble serving as a valve to cover and to uncover the series of oil holes 156, but not to cover or uncover the oil holes 155 which are diametrically aligned one with the other. A coil spring 160 surrounds the plug stem 154, abuts against the rearward wall of the plug, and also abuts at its other end against the end wall of the thimble, and this spring has a strength just sufficient to push the sliding thimble outwardly to uncover the oil holes 156 when exterior pressure on the thimble end is relieved. The outwardly-rounded head 158 of the thimble is always pressed outwardly by the spring 160 against the opposed end 161 of a stop finger 162 which by pin 163 is pivoted to a bracket 168 carried by the rear end of the arm 144 of the stop lever 137. The lower end of the stop finger is provided with a transverse pin 164 projecting on both sides, and each projecting end of the pin has connected to it a coil spring 165. The upper end of each spring is attached to the projecting neck ends 166 of the pin 163. The springs thus mounted are under tension and hold the stop finger 162 with the pivot pin 163 abutting against the under wall of a slot 167 formed through and elongated in the direc-

tion of the length of the stop finger, by the spring 165 and slot 167 construction. The stop finger 162 permits the stop lever 137 and its arm 144 to assume the position shown in Fig. 8, even if the tooth 104 is not in exact position for reception of the stop finger 162 so that it will enter the eccentric cut 105 to engage the tooth 104 on its next rotation. The bracket 168 carried by the stop lever arm 144 is slotted at 169 to receive the stop finger, the head 170 of which coacts with the stop tooth 104. The upper side of the bracket 168 projects upwardly into a slot 171 of the housing or boss a' , and the head of the stop finger reaches the stop tooth 104 of the stop sleeve 96 through the communicating slots 171, 131 and 115.

The body of oil or other lubricant contained within the thimble 157 and the bushing 151 and the plug 152, is a vitally important feature of and factor in the stop-motion mechanism. This body of oil which I show by dots marked C, constitutes a shock-absorbing cushion, which cushion is characterized by the power to absorb shock without any resultant rebound. Oil in chamber 27 of the boss reaches opposing surfaces of the stop motion through the space (Fig. 2) between the outer surface of the outer end of the top shaft extension 25^a and the inner surface of the sleeve 96. This space as an oil-receiving conduit is seen in Figs. 2 and 21 where it is indicated by 172. Thence the oil finds its way between opposing surfaces of parts and works in between the outer surface of the enlarged portion 91 of the top shaft extension 25^a and the inner surface of the enlarged portion 97 of sleeve 96, reaching the balls 99 and the wedges 94 and the walls of the wedge-receiving pockets 92.

The mode of operation of the stop motion is as follows: As shown in Fig. 8 the stop finger 162 is up against the stud 163 with its upper end in engagement with the stop tooth 104. The brake shoe 117 is in its lowermost position. The top shaft is rotatable in counter-clockwise direction as indicated by the arrow in Fig. 8, and the shaft is in its stopped position. Assuming that the stop-motion control lever 137 has its outward or forward end lifted, then the stop finger 162 will be pulled down out of engagement with the tooth 104. Simultaneously the arm 143 of the trip lever 141 will be depressed, pushing the forward end of the brake shoe lifting lever 121 downwardly and raising the pressure plug 126. Thereby the pressure of the brake shoe on the clutch sleeve 96 is relieved. The spring 111 (Figs. 14 and 21) instantly causes the stop sleeve 96 to rock, thereby forcing the balls 99 which project through the holes 98 in the stop sleeve to climb up from low to high position in the grooves 94 of the

wedges 93. Thereupon, when the balls get into this high position they wedge between the wedges and the ball-retaining ring 99^a, and as this ring is clamped in the pulley 100, rotation of the pulley rotates the ball-engaging ring and thereby the rotational movement is imparted to the balls and the wedges and as the latter are in the ball-receiving pockets of the top shaft, rotation of the top shaft is effected. On the other hand, whenever in the rotation of the top shaft the upper end of the stop finger is brought into eccentric groove 105 of the stop sleeve and rotation of the latter brings the tooth 104 against the stop finger, the stop sleeve 96 is rocked and its rocking movement carries the projecting balls 99 from the high points of the wedge grooves to the low points thereof, thus taking the balls out of contact with the ball-retaining ring. At the same time the reverse movement of the stop-motion control lever which is required to thrust the upper end of the stop finger into the eccentric groove 105, raises the arm 143 of the stop lever 141 out of pressure contact with the pressure plug lifting lever 121 and then the spring 128 expands and forces the brake shoe against the stop sleeve 96. The brake shoe presses against the reduced diametric portions 103 of the stop sleeve. The parts in question are so timed that each opposite movement of the brake shoe and pressure plug and consequently of the pressure plug lifting lever 121, slightly precedes the initial opposite movements of the stop finger in its engagement and disengagement with the tooth 104. The purpose of this timing is that the brake shoe in its braking movement against the stop sleeve 106 shall overcome the tension of the spring 111 and the fact in this connection is that when the tension of the spring 111 is relieved or as it is relieved gradually, the balls are shifted correspondingly out of interlocking relation to the ball-retaining sleeve and it is noticeable that the power transmitted through the balls to the shaft is under the control of the spring 111. The result of this is in practice that there is a minimum of shock.

I have above referred to the relation of the cap 63 to the pulley or belt wheel hub 102. The belt wheel as shown has the ends of its projecting hub annularly grooved at 102^a at each end. The outward end of the cap 63 which is endwise slidable has an annular opening, the annular edge of which faces the adjacent groove 102^a. The purpose of this is to prevent oil from the ball bearings 35 from flying onto the belt. At the other side of the pulley, the purpose of the corresponding flange 102 is to prevent any oil getting into that groove from flying onto the belt.

The stop motion in the form shown is

operable instantly to arrest the top drive shaft at the completion of any revolution, and in the sewing machine stops the drive shaft with the needle up above the work.

What I claim is:

1. The combination of a sewing-machine head having lengthwise chambered upper and under arms with a tube fixed in the upper arm chamber; top-shaft bearings for supporting a top shaft in said tube; a tubular top shaft; a tube fixed in the under arm chamber; bearings for supporting a looper shaft in the latter tube; a tubular looper shaft; means operatively connecting the top and looper shafts to secure simultaneous movement of such shafts; a stop motion for the top shaft; a drive pulley; and means for giving endwise movement to the looper shaft; and means for conveying oil to the tubular shafts. 70

2. The combination of a sewing-machine head having lengthwise chambered upper and under arms with a tube fixed in the upper arm chamber; top-shaft bearings for supporting a top shaft in said tube; a tubular top shaft; a tube fixed in the under arm chamber; bearings for supporting a looper shaft in the latter tube; a tubular looper shaft; means operatively connecting the top and looper shafts to secure simultaneous movement of such shafts; a stop motion for the top shaft; a drive pulley; and means for giving endwise movement to the looper shaft; an oil reservoir; an oil pump; an oil container and conduit communicating with the stop motion; the pump discharging into said conduit; a stop motion control mechanism constructed to receive oil from said container; the chamber of the top shaft communicating with said container and the top shaft being ported for escape of oil therefrom to stitch-forming mechanisms to be lubricated; means for conducting oil from the top shaft into the looper shaft tube; means for conducting oil from the looper shaft tube to the oil reservoir; and means for conducting oil from the top shaft into its tube and for conducting oil therefrom to the means connecting the top and looper shafts. 85

3. The combination of a sewing-machine comprising a hollow upper arm, a hollow under arm, and a trunk connecting the two arms with a top-shaft tube and supports therefor in the upper arm; a tubular top-shaft and bearings therefor in the top-shaft tube; an under tube and supports therefor in the under arm; an under tubular shaft and bearings therefor in the under shaft tube; stitch-forming devices carried by the upper shaft and cooperating stitch-forming devices carried by the under shaft; operative connections between the two shafts and located in the trunk; an oil reservoir in the trunk; an oil pump; an oil eduction con- 120

130

duit leading from the pump and communicating with the top tubular shaft; oil ports therein for escape of oil to said operative connections; an oil port therein for escape of oil to the needle-actuating devices carried by the top shaft; a dam in the front end of the top tube; conduits in the top-shaft bearings therein; means for leading oil from the upper portions of the operative connections to the lower portions thereof and from the latter into the rear end of the under shaft; ports therein for escape of oil to its bearings; a return conduit in the front bearing of the upper shaft; a return conduit in the rear bearing of the under shaft; the latter discharging into a drip-pan for the oil reservoir; the drip-pan; and an oil filter.

4. The combination of a sewing machine comprising a hollow upper arm, a hollow under arm, and a trunk connecting the two arms with a top-shaft tube and supports therefor in the upper arm; a tubular top-shaft and bearings therefor in the top-shaft tube; an under tube and supports therefor in the under arm; an under tubular shaft and bearings therefor in the under shaft tube; stitch-forming devices carried by the upper shaft and coöperating stitch-forming devices carried by the under shaft; operative connections between the two shafts and located in the trunk; an oil reservoir in the trunk; an oil pump; an oil eduction conduit leading from the pump and communicating with the tubular top shaft; oil ports therein for escape of oil to said operative connections; an oil port therein for escape of oil to the needle-actuating devices carried by the tubular top shaft; a dam in the front end of the tubular top shaft; conduits in the top-shaft bearings therein; means for leading oil from the upper portions of the operative connections to the lower portions thereof and from the latter into the rear end of the under shaft; ports therein for escape of oil to its bearings; a return conduit in the front bearing of the upper shaft; a return conduit in the rear bearing of the under shaft; the latter discharging into a drip-pan for the oil reservoir; the drip-pan; and an oil filter.

5. A sewing-machine head comprising lengthwise-chambered upper and under arms connected by a chambered trunk, the chamber whereof connects with the chambers in the arms, the head being provided in its trunk portion with a chambered oil-receiving boss; an oil reservoir; an oil pump arranged to discharge oil from the reservoir into the chamber of the boss; a tube fixed in the chamber of the upper arm; bearings in said tube for the drive shaft; said drive shaft mounted in said bearings and being lengthwise chambered; a tube fixed in the chamber of the lower arm; bearings in said

lower tube for a looper shaft; said looper shaft formed with a lengthwise-extending chamber; stitch-forming mechanisms; means connecting the upper shaft with the looper shaft to secure endwise reciprocation thereof; means connecting the upper shaft with the looper shaft to effect oscillation thereof; a stop-motion comprising a belt wheel operatively connected with the upper shaft; a pump driving pulley; and a belt common to the belt wheel and pump driving pulley.

6. A sewing-machine head provided with lengthwise chambered upper and under arms connected by a chambered trunk the chamber whereof communicates with the chambers of the arms; a top drive-shaft; a looper shaft; stitch-forming instrumentalities; mechanism connecting the top drive-shaft with the looper shaft to move the looper shaft endwise; mechanism connecting the top drive-shaft with the looper shaft to effect oscillation of the latter; a stop-motion mechanism operatively connected with the drive-shaft; the said looper-shaft actuating mechanisms and stop-motion being contained in the chamber of the trunk and housed thereby; an oil-containing reservoir; an oil pump supported by the reservoir; the reservoir being supported forwardly of the rear wall of the trunk; and an eduction tube from the pump being located within the chamber of the pump; the trunk chamber containing an oil container into which the eduction tube discharges; and the stop motion having exposed in said oil chamber an oil-receiving space whereby the stop motion receives oil from said chamber.

7. A sewing-machine head having lengthwise chambered upper and under arms and a chambered trunk, the chamber whereof communicates with the chambers of said arms; a drive shaft mounted in one of said arms; a looper shaft mounted in the other of said arms; stitch-forming instrumentalities; the said shafts being tubular; an oil reservoir having a drip pan at the bottom of the trunk chamber; an oil pump mounted in said reservoir; the trunk chamber containing an oil container, an eduction pipe from the pump in the reservoir and discharging into said oil container; and the rear end of the top-shaft chamber being exposed in said oil-containing chamber.

8. A sewing-machine head having lengthwise chambered upper and under arms and a chambered trunk, the chamber whereof communicates with the chambers of said arms; a drive shaft mounted in one of said arms; a looper shaft mounted in the other of said arms; stitch-forming instrumentalities; the said shafts being tubular; an oil reservoir having a drip pan at the bottom of the trunk chamber and an oil pump

- mounted in said reservoir; the trunk chamber containing an oil container, an eduction pipe from the pump in the reservoir and discharging into said oil container; and the 5 rear end of the top-shaft chamber being exposed in said oil-containing chamber; a driving pulley for the top shaft and a belt therefor; the drip pan having a walled hole through it for passage of the belt.
- 10 9. In a sewing-machine, the combination of an oil reservoir; an oil pump; a drive-shaft having a lengthwise bore constructed and arranged to receive oil from the pump; a needle crank fixed on the front end of the 15 drive shaft, the bore whereof is connected by an oil conduit with the crank shaft; a needle-actuating link; a needle carrier; and a guide for the needle carrier, the guide being provided with an oil conduit to receive 20 oil flying off the needle link.
10. The combination of an implement-car-
- rying head having a drive-shaft; stop-motion members inclosing such shaft and formed with a lubricant-receiving port; and a lubricant reservoir fixed to said head and 25 containing a lubricant pump having an eduction conduit for discharge of lubricant to said port.
11. The combination with upper and under conduit-forming shafts having lubricant intake and exit ports, of means operatively connecting said shafts for operating them in unison; a stop-motion operatively combined with one of the shafts; means for actuating the stop motion; a lubricant pump; and conduit connections for delivering lubricant to said shafts and stop motion the members of which are provided with ports for reception of the lubricant.

In testimony whereof I have hereunto set 40
my hand this 3d day of April, 1916.

JOHN PETER WEIS.
